UNITED STATES PATENT OFFICE.

BERTHA S. CRAMER, OF MINNEAPOLIS, MINNESOTA.

COMBINATION SKIRT-MARKER, BIAS-FOLDER, AND PATTERN-MARKER.

1,108,143.

Specification of Letters Patent.

Patented Aug. 25, 1914.

Application filed December 7, 1912. Serial No. 735,491.

To all whom it may concern:

Be it known that I, BERTHA S. CRAMER, a citizen of the United States of America, residing at Minneapolis, in the county of 5 Hennepin and State of Minnesota, have invented certain new and useful Improvements in a Combination Skirt-Marker, Bias-Folder, and Pattern-Marker, of which the following is a specification, reference being 10 had therein to the accompanying drawing.

This invention relates to skirt markers and gages, and has for its object the production of an efficient instrument which may be used for a number of purposes, such 15 as in marking patterns, in marking skirts, and also as a bias folder.

Another object of this invention is the production of a simple and efficient instrument which may be readily detached so as 20 to separate the several parts thereof.

With these and other objects in view, my invention consists, in general, of certain novel arrangements and combinations of parts, as will be hereinafter fully described 25 and claimed.

In the accompanying drawing: Figure 1 is a perspective view of the device used as a skirt marker. Fig. 2 is a vertical section thereof. Fig. 3 is a rear view of the gage 30 of the skirt marker, showing the base of the marker in section. Fig. 4 is a transverse section taken on line 4—4 of Fig. 2. Fig. 5 is a detail perspective of the device as used as a bias folder.

By referring to the drawings, it will be seen that 1 designates the base which is formed of sheet-metal or other desired material, having downwardly-extending flanges 2 for constituting a support for the base. 40 The gage 3 is placed upon the base 1 and comprises a rear plate 4 and a front plate 5. This plate 5 is provided with a cut-out portion 6 for allowing the marking chalk to extend therethrough. The rear plate 4 and the front plate 5 are connected by means of an integral bridge portion 7, and this bridge portion 7 is provided with a notch 8 formed in one end thereof, through which works a thumb-screw 9. This thumb-screw 9 passes 45 through a threaded aperture formed in the base 1 for holding the gage 3 in a set position upon the base 1. The rear plate 4 is provided with a plurality of side flanges 10 in which is placed a narrow strip of chalk 55 11 for use when using the gage as a pattern marker.

An adjustable marker 12 is slidably mounted upon the front plate 5 and comprises a chalk-holding plate 13 having a central aperture 14 for receiving a marking chalk 15. A binding plate 16 passes transversely of the plate 5. A thumb screw 19 passes through the binding plate 16 and clamps the plate 13 and the binding plate 16 in engagement with the plate 5, so as to 60 hold the marker in an adjusted position upon the plate 5. Of course, it will be understood that the plate 5 may be provided with a plurality of graduations for facilitating the adjustment of the marking device 12 upon the plate 5 if it be so desired. 65

When the device is used as a bias folder, the marker device 12 is removed from the plate 5 and the material to be folded is folded between the spaced portions of the 70 plates 4 and 5. Since the plate 5 is graduated throughout its entire length, it will be understood that the gage may be held in such position as to allow the desired width fold to be made between the plates 4 and 5. 75 Of course, it will be understood that while the gage is used as a bias folder, the gage 3 is removed from the base 1. The adjustable marker 12 is provided with an angle end 20 which angle end is provided with an enlarged aperture 21 through which passes the rear plate 4. A smaller aperture 22 is formed parallel with the wide aperture 21 and the plate 5 passes through this narrow aperture 22. The set screw 19 through the 80 medium of the plate 16 firmly holds the adjustable marker 12 in a set position upon the plates 5 and 4. 85

When the device is used as a bias folder as illustrated in Fig. 5, the plate 4 is passed 90 through the wide aperture 21 and the plate 5 through the narrow aperture 22 of the clamping section 12. The binding plate 16 is placed under the plate 5 and the plate 13 of the adjustable marker 12 overhangs the 95 outer face of the plate 5. A thumb-nut 19 firmly clamps the two plates 12 and 16 in engagement with the plate 5 so as to hold the section 12 in position upon the plates. The thumb-nut 19 passes through the notch 100 105 23 formed adjacent the aperture 14. The goods which is to be folded is then run between the outer ends of the plates 5 and 4 when the device is in the position illustrated in Fig. 5.

When the device is used as a skirt marker, the section 12 is so placed upon the plates 5 110

and 4 as to have the plate 13 extend between the plates 5 and 4. It will, therefore, be seen that when the skirt adapted to be marked is placed between the plates 5 and 4, the chalk 15 will cause the skirt to be marked upon one side, whereas the pressure of the chalk will cause the skirt to be marked upon the other side by bearing against the chalk stick 11. Of course, the device may be used 10 as a pattern marker in the same manner as a skirt marker, the material being placed between the plates 5 and 4 and being marked by the chalk sticks 11 and 15.

When the device is used as a pattern marker it should be understood that the adjustable marker 12 is loosely mounted upon the plate 5 so as to slide thereon and facilitate the marking of the goods from the pattern according to the perforations formed in 15 the pattern. By allowing the clamping section 12 to slide freely upon the plate 5, by loosening the thumb screw, it will be seen that the pattern may be easily marked since the marking chalk 15 will press upon the 20 goods to be marked and thereby cause an impression to be made upon the opposite side of the material by means of the chalk stick 11. In using the device, the material is doubled upon the table having the pattern 25 attached thereto and drawn through between the plates 4 and 5. The adjustable slide is loosely fastened and can then be drawn to each perforation of the pattern, marking both sides exactly the same, the 30 idea being to get both right and left sections of a waist, skirt, etc., with the same perforations on each one at the same time. By having the adjustable marker movable on the plate 5 it will be seen that the marker may 35 be easily moved longitudinally of the plate 5 for placing an indicating mark upon the material being marked without changing the position of the plate 5.

When the device is used as a skirt marker the thumb screw 19 is clamped upon the 45 front plate 5 as illustrated in Fig. 1.

When the device is used as a bias folder the plate 16 is placed under the plate 5 and the thumb nut 19 is placed upon the top of the adjustable marker 12 as illustrated in 50 Fig. 5.

What I claim is:

1. A device of the class described, comprising a base, a vertical gage carried by said base and comprising a pair of spaced 55 plates connected together by means of an integral bridge portion, said integral bridge portion provided with a notched portion at one end, a thumb screw passing through said notched portion for detachably securing said 60 gage to said base, an adjustable plate slidably mounted upon one of said spaced plates, a marking chalk carried by said adjustable plate, and means for securing said adjustable plate in a locked position upon one of 65 said spaced plates.

2. A device of the class described comprising a front plate and a rear plate, a marker device slidably mounted upon said front plate, a stick of chalk carried by said 70 marker device, the rear plate provided with a channel formed therein, a second stick of chalk positioned within said channel, and said first mentioned stick of chalk adapted to mark upon one side of a sheet placed between said front and rear plates for causing 75 said last mentioned stick of chalk to mark upon the opposite side of said sheet by means of the pressure of said first mentioned stick of chalk upon said sheet.

In testimony whereof I hereunto affix my signature in presence of two witnesses.

BERTHA S. CRAMER.
